Primary Examiner — Patricia A Palasik(74) *Attorney, Agent, or Firm* — Dorsey & Whitney LLP(57) **CLAIM**

The ornamental design for a cutting tool, as shown and described.

DESCRIPTION

FIG. 1 is a front, perspective view of a cutting tool;
FIG. 2 is a front elevational view thereof;
FIG. 3 is a back elevational view thereof;
FIG. 4 is a side elevational view thereof, with the other side
elevational view being identical;
FIG. 5 is a top plan view thereof; and,
FIG. 6 is a bottom plan view thereof.
The broken lines in the drawings depict unclaimed environmental subject matter.
